UNITED STATES PATENT OFFICE.

WILLIAM H. LEWIS, OF BROOKLYN, ASSIGNOR TO E. & H. T. ANTHONY & COMPANY, OF NEW YORK, N. Y.

PHOTOGRAPH-CAMERA SHUTTER.

SPECIFICATION forming part of Letters Patent No. 367,986, dated August 9, 1887.

Application filed April 30, 1886. Serial No. 200,061. (No model.)

To all whom it may concern:

Be it known that I, WILLIAM H. LEWIS, of Brooklyn, in the county of Kings and State of New York, have invented a new and useful Improvement in Photographic-Camera Shutters, of which the following is a specification, reference being had to the annexed drawings, forming a part thereof, in which—

Figure 1 is a front elevation of my improved camera-shutter. Fig. 2 is a side elevation. Fig. 3 is a perspective view showing the rear of the camera-shutter. Fig. 4 is a detail perspective view of the shutter.

Similar letters of reference indicate corresponding parts in the different figures of the drawings.

The object of my invention is to provide a simple, inexpensive, and efficient camera-shutter which may be readily applied to any photographic camera, and which may be used for making either a time or instantaneous exposure.

My invention consists in a circular shutter-body provided with an aperture at one side of the center thereof, and having a fastening device for attaching it to the camera-tube, a circular shutter pivoted to the shutter-body and apertured at one side of the center, having notches in its edge, a lever pivoted to the shutter-body and arranged to engage one or the other of the notches of the shutter, and a pneumatic device for moving the shutter-engaging lever.

It also consists in the combination, with the shutter, of a lever carrying an adjustable weight and connected by a cord with the boss of the shutter.

It also further consists in a movable stop for limiting the motion of the shutter-engaging lever when it is desired to make a time exposure.

The body A of the shutter is provided with a circular opening, B, at one side of the center thereof, and with an annular groove, a, in the rear side, which is concentric with the opening B, and is designed to receive the end of the camera-tube. At one side of the annular groove is secured a curved plate, b, to which are pivoted two curved arms, c, which are oppositely arranged with respect to each other, and are provided with notched ends d, received between a binding-screw, e, and a plate, f, secured to the back of the shutter-

body when the arms c are closed around the flange of the camera-tube C, as shown in Fig. 55 2. The opposite or front side of the shutter-body A has a circular recess, g, in which is placed a circular shutter, D, provided with a circumferentially grooved boss, h, which is mounted revolvably on a stud, i, projecting in 60 the axis of the shutter-body A from a plate, j, secured to the back of the shutter-body. The shutter D has an opening, k, corresponding to the opening B of the shutter-body, and in the periphery of the shutter D are formed 65 the notches l m.

To an arm, n, secured to the front of the shutter-body, near its periphery, is pivoted a forked lever, E, having the long arm o and a short arm, o'. To the short arm o' is connected a cord, p, which is wound partly around the boss h in the groove thereof, and secured to the boss by passing it through a hole near the edge of the boss and tying it in a knot or in any other convenient way. To the arm o 75 of the lever E is fitted the slide q of the adjustable weight F. A set-screw, r, passes through the side of the slide q, and clamps it in any required position on the arm o. The weight F is preferably made cylindrical in 80 form, and the slide q is attached to the end of the weight nearest the pivot of the lever E, to permit of projecting the opposite end of the weight beyond the end of the arm o when desirable. 85

To the face of the body A is pivoted a curved lever, G, on the screw s, which lever is provided at one end with an outwardly-projecting arm, t, and also with an arm, u, projecting into the recess g in position to engage the 90 notch l in the edge of the shutter D. The end of the lever G on the opposite side of its pivot is provided with an arm, v, which projects into the recess g in position to engage the notch m in the periphery of the shutter D. 95 This end of the lever G is also provided with an arm, w, projecting outwardly toward the periphery of the body A, and on the periphery of the body is placed a curved slotted plate, a', provided with a finger, b', projecting beyond the face of the shutter and capable of being moved forward opposite the arm w. The plate a' is held in position on the periphery of the body A by screws c', passing through a slot in the body of the plate. The body A is provided with a stop-pin, d', for limiting the mo- 100 105

tion of the lever G when the finger b' is withdrawn from the path of the arm w on the lever.

A pneumatic cylinder, H, is supported by a plate, e', secured to the periphery of the body A, and contains a piston, f', the end of which touches the arm t, carried by the lever G. The V-shaped spring m', connected with the plate e' and with the arm t, tends to draw the arm t and the end of the lever G, with which it is connected, toward the periphery of the body A and in opposition to the outward pressure of the piston f'. The other end of the cylinder H is connected by a flexible tube, g', with a pneumatic bulb, h'.

15 The shutter D is provided with a triangular projection, i', and arms j' k' project from the body A over the shutter D and in the path of the triangular projection i'. The arm k' is bent outward so as to present an inclined surface to the triangular projection i' and thus arrest the motion of the shutter without jarring the camera. The arm k' limits the forward motion of the shutter, and the arm j' limits the return motion of the shutter. To 20 the boss h is secured an arm, l', by which the shutter is returned to the point of starting after having been released for making an exposure. A segmental plate, I, which is secured to the face of the body A, extends over the upper 25 edge of the shutter D, and prevents the light from passing around the edge of the shutter at that point.

The operation of my improved shutter is as follows: The weight F having been adjusted 30 on the arm o, so as to secure the desired rapidity of motion in the shutter D, the shutter is turned backward, (into the position shown in full lines in Fig. 1,) winding the cord p around the boss h of the shutter and bringing 35 the notch m under the end of the lever G, permitting the arm v to drop into the notch, thus holding the shutter in a closed position, with the weight F raised in position to turn the shutter when released. If it is desired to 40 make an instantaneous exposure of the plate, the finger b' is moved forward over the arm w, thereby limiting the motion of the lever G to the amount required to release the arm v, carried by the lever from the notch m in the periphery of the shutter D, and preventing the 45 arm u from dropping into the notch l. Pressure upon the bulb h' forces air into the cylinder H, which pushes out the piston f' and releases the shutter, so that it is immediately 50 turned through a part of a revolution by the action of the weight F, through the medium of the lever E and the cord p, thus carrying the opening k past the opening B and past the end of the camera-tube. By moving the weight 55 F outward on the arm o the rapidity of the exposure is increased.

When it is desired to make a time exposure, the finger b' is moved away from the path of the arm w, so that when the arm v, carried by 60 the lever G, is released from the notch m the arm u, carried by the opposite end of the lever, will be pushed inward into the notch l,

so that the motion of the shutter D is arrested when the opening k of the shutter coincides with the opening B of the shutter-body and 70 with the opening of the camera-tube. The exposure continues so long as pressure is created on the piston f' by compressing the bulb h'; but when the bulb h' is released the spring m' returns the lever G and piston f' to their normal position, thus releasing the shutter D and allowing it to be moved forward by the action of the weight F and close the opening. 75

To provide for holding the shutter permanently open while focusing, or for a very long 80 exposure, a pin, n', is inserted in a hole in the shutter-body through the notch l.

By means of my improvement I am enabled to secure a uniform movement of the shutter D, which may be easily regulated by adjusting 85 the weight F on the arm o.

It is obvious that the cord p may be attached to the arm o of the lever E, and that the adjustment of the weight F may be effected by reversing it on the arm o when it is desired 90 to bring the weight near the pivot of the lever E. It is also obvious that the opposite end of the cord p may be secured to some part 95 of the shutter-disk instead of being wrapped partly around the boss.

In case it becomes necessary to connect the shutter with the camera-box independently of the camera-tube, the arms e and binding-screw e will be dispensed with, and other and well-known means of fastening will be employed. 100

Having thus described my invention, what I claim as new, and desire to secure by Letters Patent, is—

1. The combination, with the oscillating shutter D, provided with the notches l m, and the projecting portion intermediate between the notches, of the lever G, provided with arms u v, arranged to be received in the notches in alternation, the notch l being shorter than the notch m, as herein specified. 110

2. The combination, with the shutter D, provided with notches l m, and the weighted lever E, of the lever G, provided with the arms u v w, and the plate a', having the finger b' for limiting the motion of the lever G, substantially as herein shown and described. 115

3. The combination, with the shutter D, provided with notches l m, and the weighted lever E for moving the shutter, of the lever G, provided with arms u v t, and the pneumatic cylinder H, having the piston f' arranged to engage the arm t and the V-shaped spring m' arranged to oppose the action of the piston f', substantially as shown and described. 120

4. The combination, with the shutter-body A, provided with the opening B and annular groove u, of arms e and means, substantially as shown and described, for clamping the arms in a closed position. 125
